METHOD AND APPARATUS FOR DOING
HECTOGRAPH AND OTHER PRINTING

Fred R. Bartholomew, Minneapolis, Minn.

Application April 23, 1938, Serial No. 203,917

10 Claims. (Cl. 101—131)

This invention relates to a new and improved method and device for doing hectograph printing, the device also comprising a combination upon which stencil printing may be done. The invention is particularly directed to such a combination comprising rotating members forming in effect a rotary press.

At present hectograph printing is done either on a flat bed press or on a rotary cylinder press. In both types of presses a gelatin film is carried on a member and the material to be printed is pressed against this film and is later stripped or pulled therefrom. To prepare said film for the printing operation a master copy carrying an image in hectograph ink is placed face down on the hectograph gelatin film and allowed to remain there under slight pressure until the gelatin film has absorbed a considerable part of the hectograph ink. The master copy with the remainder of the hectograph ink thereon is then removed from the gelatin film and the value of the master copy is wasted to the extent of the ink that remains on it. After this hectograph ink has been absorbed by the gelatin film or transferred thereto as described this ink in the printing process is transferred by the gelatin film to successive sheets of paper brought into engagement with the film. This is continued until the prints on said paper finally become too faint to be usable. With this method now in use therefore, all of the ink is not transferred from the master copy to the film and the sheets of paper that take the first impressions from the gelatin film will have very dark or heavy printing thereon and the sheets of paper that take the last impressions from the gelatin film will have correspondingly light printing thereon.

Furthermore, the printing done on the flat press above referred to is all hand work and therefore very slow. On the rotary cylinder press the speed of production can be increased considerably. However, one requirement of hectograph printing is that the print must remain on the gelatin film until sufficient ink has been transferred from the gelatin to the paper or other material. This necessitates that the paper must follow the gelatin film around the cylinder sufficiently long for the desired amount of ink to be transferred from the gelatin. It is true that under present methods the cylinder may be revolved very fast at first and satisfactory production obtained because the first prints need only remain on the gelatin for a very short time. However, as the ink is used off from the gelatin the paper must remain thereon for a longer time

if a satisfactory print is to be obtained. The present method therefore, is either to slow up the speed of the cylinder after the print appears too light or to allow the paper to remain upon the cylinder and gelatin for several revolutions before stripping the paper therefrom. Obviously either of these methods reduces the production. Due to the fact that heavy cardboard will not bend around the cylinder such cardboard cannot

10 be printed on a rotary or cylinder type hectograph press.

It is an object of this invention, therefore, to provide a novel method and apparatus by means of which the paper or material to be printed may remain in contact with the gelatin for a longer or shorter period without reducing the speed of production.

It is also an object of the invention to provide a machine by which both stencil and hectograph printing may be done.

20 It is still further an object of this invention to provide an attachment by the use of which prints made from a gelatin film will not vary as to intensity as under the present methods and 25 by the use of which a greater amount of the ink can be taken from the master copy.

It is still another object of the invention to provide a simple and efficient hectograph rotary printing machine upon which heavy cardboard 30 that will not bend around the cylinder may be printed.

These and other objects and advantages of the invention will be fully set forth in the following description made in connection with the 35 accompanying drawings in which like reference characters refer to similar parts throughout the several views and in which:

Fig. 1 is a view in side elevation of the device;
Fig. 2 is a partial view in side elevation of a 40 modified form of the device;

Fig. 3 is a view in vertical section of the device shown in Fig. 2 taken substantially midway of the machine;

Fig. 4 is a view in vertical section taken substantially on line 4—4 of Fig. 7;

Fig. 5 is a partial view similar to Fig. 4 shown on an enlarged scale;

Fig. 6 is a view in vertical section taken substantially midway of a modified form of the 50 machine;

Fig. 7 is a view in end elevation of the machine shown in Figs. 1 and 4;

Fig. 8 is a plan view of a portion of the belt used; and

Fig. 9 is an end view of a segmental cover used;

Referring to the drawings, particularly Figs. 1, 4 and 7, a machine is shown comprising a frame member 15 having spaced side portions 15a in which is journalled a shaft 16 on which a cylinder or drum frame 17 is mounted. Frame 17 comprises a pair of laterally spaced rings 17a having hub portions and a plurality of arms 17b connected thereto. A cylinder 18 having a peripheral surface overlies and extends between the rings 17a, said cylinder being formed by a segment 18a extending through substantially half the circumference of rings 17a. A segmental plate 18b engages the end of segment 18a and completes the periphery of cylinder 18. Shaft 16 may be rotated by power or by hand in any suitable manner as by a crank handle 20 secured to the end thereof at the outer side of one of the end portions 15a. A gear 21 is secured to shaft 16 adjacent one of the end members 15a and this gear meshes with a gear 22 secured to a drum or cylinder 23 carried on a shaft 24. Shaft 24 is mounted at its ends in auxiliary frame members 25 having base portions 25a secured to the top of each side member 15 as shown in Fig. 1. Members 25 will be secured by suitable screws 26. Members 25 have standard portions 25b, the same being provided with open ended slots 25c in their upper ends. Shaft 24 has end portions rectangular in cross section adapted to fit and slide vertically in the slots 25c and which are thus held from rotation. Screws 27 extend through the end portions of shaft 24 and engage the members 25b, said screws having suitable hand wheels 27a at their upper ends. Shaft 24 can thus be adjusted vertically. The drum 23 is rotatably mounted on shaft 24 and gear 22 is secured to said drum by a plurality of circumferentially spaced screws 28. Drum 23 may be perforated for substantially half of its periphery and the other half of said periphery comprises a removable segment 23b overlying offset extensions 23a of the drum 23 and suitably secured thereto by screws 29. A platen roll 30 has trunnions journalled in the side members of the frame 15 and extends between the same, the surface of said roll being a short distance below the bottom of the cylinder member 18. A feed table 31 is also mounted in frame 15 beneath said drum and extends to a point adjacent roll 30, the top surface of said table being substantially in the same plane as the top surface of roll 30. Another frame member 32 is provided having substantially the same width as frame 15 and said frames will be mounted upon some suitable rigid base member 33. One or both of said frames may be arranged for guided sliding movement on said base. Frame 32 has spaced side portions 32a and a shaft 33 is journalled in and extends between said side portions, the same having rigidly secured thereto a cylinder or drum 34. Shaft 33 also has a crank handle 35 secured to one of its ends just outside one of the frame members 32a by means of which it can be rotated. A belt 36 is arranged to pass over and between the cylinder 34 and the cylinder 18. This belt has thereon spaced gelatin films 37 such as commonly used in hectograph printing. Films 37 are shown as having rectilinear adjacent edges extending at right angles to the edge of belt 36. Said belt preferably has formed therein a series of openings 36a adjacent one edge adapted to fit over suitable teeth or projections 18c carried on and adjacent the edge of cylinder 18. Cylinder 34 has secured at one end a gear 38 meshing with a gear 39 secured to a stripping roller

40 carried on shaft 41, said shaft having its ends journalled in frame members 32a. Gear 39 meshes with another gear 42 secured to a stripping roller 43 spaced a short distance from roller 40. Roller 43 is carried on a shaft 44 having its end portions journalled in frame members 32a. Cylinder 34 also has therein at one end teeth 34a for engagement in openings 35a of belt 36.

A feeding table 45 may be provided adjacent the upper side of cylinder 18, the same being carried by bars 46 secured to the side thereof and secured to the outer sides of frame members 15a and 15b. An angle bracket 47 may also be secured to the ends of frame members 15a and 15b, the same projecting outwardly some distance over table 45. A scraper or presser member 48 is secured to member 47 and depends therefrom to a point adjacent belt 36. Member 48 has a rounded lower edge disposed in a plane a short distance above the top of feeding table 45 or in a line disposed substantially at the top of the gelatin film as it passes around the cylinders. It will be understood that member 48 extends across the entire width of the film 37 and preferably a short distance at either side.

In Fig. 4 a plurality of sheets of material 49 and 50 are shown attached to drum 23 representing respectively an absorbent sheet and a stencil and while these can be held on said drum in various ways in the embodiment of the invention illustrated they are shown as held by the ends of segment 23b where it overlaps the portions 23a and is held by the screws 29.

Frames 15 and 32 will preferably be mounted for relative movement toward and away from each other and some resilient means preferably will be provided relatively to move said frames apart. While various means could be provided, in the embodiment of the invention illustrated a rod 55 is shown of cylindrical form which may be flattened at one end and secured to frame 15 in any suitable manner as by a screw 56. Rod 55 at its other end extends into and is slidable in a tube 57 which also may be flattened at one end and secured to frame 32 in any suitable manner as by the screw 58. Rod 55 is threaded at 55a and a collar 59 is disposed on said rod with which engages a nut 60 threaded on portion 55a. A collar 61 is secured on tube 57. A compression coiled spring 62 surrounds tube 57 having one end engaging collar 61 and its other end engaging collar 59. With this arrangement it will be seen that spring 62 acts to move frames 15 and 32 away from each other and belt 36 will thus be suitably tightened or kept under the desired degree of tension. If desired, a member 55 and a member 57 with the attendant structure may be disposed at each side of the frames 15 and 32.

The machine may be furnished without brackets 25 and the parts carried thereby and only bracket 47 used. The resilient scraper or pressure member 48 secured to the undersurface of bracket 47 will be used and as stated, its edge is disposed in a line a slight distance above the top of feeding table 45 or substantially at the top of the gelatin films which move thereunder.

In operation, when offset hectograph printing is to be done a master copy will be made represented by sheet 49 as shown in Fig. 4. It will be understood that stencil 50 is not used at this time. The hectograph ink will be, of course, applied to the outer side of sheet 49. The belt 36 is now driven by the operator turning either crank 20 or 35. A sheet of paper 53 can now

be fed from table 31 over the platen roll 30. It will be understood that platen roll 30 merely revolves freely and is not positively driven. Any of the well known paper feeders now in use in the art may be used if desired to feed the paper the desired distance. The paper is fed a certain distance over the top of platen roll 30 and is then engaged by the forward edge of one of the films 37. Said paper will adhere to said film and be carried along thereby. As the films 37 pass between cylinders 18 and 23 the image from the master copy 49 is successively transferred to said gelatin films. When a film 37 passes around cylinder 18 and engages the paper 53, said paper is pressed against the film by the platen roll 30. The gelatin film is quite adhesive and the paper remains thereon and passes along the lower run of belt 36. The image is thus transferred by the film to the paper. The portion of the paper which is projecting beyond the gelatin film moves to and is engaged by the stripping rollers 40 and 43 which are being rotated by gears 38, 39 and 42 and as the belt and gelatin film move around the cylinder 34 the paper is thus stripped from the film. The machine can thus be used to do hectograph printing in an offset manner. If cardboard is to be printed it is similarly fed on the table 31 some distance over the top of platen roll 30 and is then engaged by the gelatin film. The cardboard will be pressed against the film by roll 30 and will adhere to said film and be carried along therewith. The film and cardboard advance until cylinder 34 is reached, and the cardboard being stiff, then continues to move in the same straight line and it may be stripped by rollers 40 and 43 or it may simply pass forward and be dropped by the machine without any stripping mechanism being used. The paper or cardboard can be kept in contact with the gelatin film a longer time by lengthening the belt 36.

The paper may also be fed to the machine from the table 45. When so fed it will remain in contact with the gelatin for a longer period of time than when fed from table 31. This may be desirable when the copies become somewhat lighter or weaker, as when the master copy has been used for a considerable time or when the ink on the films 37 has been used for quite a period if the offset method is not used.

The paper may be moved forward on table 45 by hand or with any desirable feeder now known in the art until the paper is in position to contact the end of the gelatin film as it passes around the cylinders. The paper is fed into this position after one gelatin film has passed and before the next film has arrived at this point occupied by the end of the paper. The paper may be fed to the point when it touches the non-adhesive portion of the belt between the 60 gelatin films. With the paper thus positioned, it is engaged by the forward edge of the gelatin film moving upwardly over cylinder 18 and will be pressed against said gelatin film by the scraper or presser 48 which will engage the side of the paper across the entire width thereof. Scraper 48 will be flexed or bent somewhat as indicated in dotted lines in Fig. 1. The paper then continues around cylinder 18 and will be stripped from the gelatin film upon reaching the rollers 40 and 43 as already described. Said paper will merely be pressed against the gelatin film as it passes over roll 30. It is understood that the presser 48 and the platen roll 30 may

be used interchangeably for the same purpose of pressing the paper onto the gelatin film.

The cylinder 18 shown and described may be the well known cylinder of a standard duplicating machine now commonly used in the art such as a "Multigraph" or "Mimeograph" machine. Such a machine can thus be converted into the present machine. Many of such duplicating or stencil machines have a complete cylinder while other machines have only a segment of a cylinder on which to place the stencil as above described. It is, of course, apparent that the present machine is not limited to the structure of a standard or other type of duplicating or stencil machine. The use of a stencil machine with this invention would save the user the cost of supplying a revolving cylinder. Also to those users who have no stencil machine but wish to do stencil and hectograph printing the machine as shown in the drawings and specification could be supplied.

A further method of doing both hectograph and stencil printing on this machine at the same time could be accomplished by placing the stencil 50 over an absorbent sheet which would replace sheet 49 on the cylinder 23, the said absorbent sheet being supplied with ink in any of the usual ways. The cylinders 23 and 18 would then be revolved in unison as described and a sheet of 30 paper could be fed onto the gelatin film from feeding table 45. As this paper sheet passed under the cylinder 23 it would be printed by the stencil thereon. The sheet of paper would thus be printed on one side by the stencil and would be printed on the opposite side by one of the 35 hectograph gelatin films 37.

In the form shown in Figs. 2 and 3 and when a master copy is not used on cylinder 23 the image would be transferred to the gelatin film 40 in the manner now common by placing the master copy thereon for a certain period. The paper will be fed from the table 45 as already described or the paper or cardboard may be fed from the table 31 with which the machine will be provided as shown in Figs. 1 and 4. The paper will be stripped from the gelatin films in the manner already described.

In Fig. 6 a frame 65 is shown which like frame 15, will have side portions in which is journaled 50 a shaft 66 similar to shaft 16. A cylinder 67 having thereon a segment 68 and a segment 68a completing a cylinder is carried on shaft 66. Shaft 66 will be provided with suitable means for rotation as already indicated. Another frame member 70 is provided which like frame member 15 will have spaced side portions in which is journaled a shaft 71. A cylinder 72 having segments 73 and 73a will be carried on member 72. A belt 74 is provided which runs around the cylinders 68 and 73. This belt will have thereon spaced gelatin films 75 similar to the films 37. Platen rollers 76 and 77 are provided adjacent cylinders 68 and 73, roll 76 being at the bottom of cylinder 68 and carried on a shaft 78 journaled at its ends in the sides of frame 65. Roll 77 is disposed at the top of cylinder 73 and is carried on the shaft 79 which will be journaled in suitable lugs forming part of frame member 70. A feeding table 80 is carried by frame 65 shown at the left of plate roll 76 and a feeding table 81 is shown adjacent roll 73 and at the right of platen roll 77. A pair of stripping rollers 82 and 83 are mounted on shafts 84 and 85 respectively which will be mounted in portions of frame 65. Rollers 82 and 83 may

be rotated by some suitable mechanism (not shown), such as the gears shown in Fig. 1. Another pair of stripping rollers 86 and 87 are shown at the lower part of cylinder 73, said rollers being carried on shafts 88 and 89 respectively journaled in frame 70. Rollers 86 and 87 will be preferably rotated by some suitable mechanism (not shown) similar to that for rotating rollers 40 and 43.

Frames 65 and 70 will rest upon some suitable base or support and will preferably be arranged thereon for relative movement toward and from each other. Preferably the frames are urged apart by a resilient means to properly tension belt 74. While various mechanisms could be used for this purpose, in the embodiment of the invention illustrated a rod 90 is provided shown as flattened at one end and secured to frame 65 by some suitable means such as the screw 91. Rod 90 at its other end extends into a tube 92 in which it is slidable, said tube being shown as having its remote end flattened and secured to frame 70 in some suitable manner as by the screw 93. Rod 90 is threaded as shown at 90a and a collar 94 surrounds said rod, the same being engaged by a nut 95 on the threaded portion 90a. A collar 96 is secured to tube 92 in any suitable manner and a coiled compression spring 97 surrounds tube 92 having one of its ends engaging collar 96 and its other end engaging collar 94. With this construction it will be seen that spring 97 will urge frames 65 and 70 apart thus tensioning belt 74. The degree of compression of spring 97 may be regulated by adjustment of nut 95. If desired, there may be one of the rods 90 and tubes 92 with the attendant parts at each side of the frames 65 and 70.

In operation of the device shown in Fig. 6 the paper may be fed from table 81 to a point a short distance beyond roll 71 by hand or by some suitable automatic feeder. The paper will be engaged by a film 75 as the latter rotates with cylinder 72, and pressed thereagainst by platen roll 71. The paper will be carried along on film 75 and may then be stripped by the stripping rollers 82 and 83. If desired, the stripping rollers 82 and 83 may not be used and the paper will continue on the belt passing between platen roll 76 and the film and will then be stripped by the stripping rollers 86 and 87. In the latter case the paper will remain on the gelatin film for quite a long period. A good print will thus be insured. Paper may also be fed simultaneously from both the tables 80 and 81 to the films 75, the paper being fed from table 81 being stripped by rollers 82 and 83 and the paper being fed from table 80 being stripped by rollers 86 and 87. With such operation the production of prints will be doubled. It will also be seen that cardboard may be fed from either or both tables 80 and 81 and be printed by the gelatin films. The length of the belt 74 can be such that the paper or cardboard will remain on the gelatin film for the desired period. The lengthened belt could be run at the same speed and it would thus not be necessary, as in prior machines to reduce speed and production in order to have strong prints.

It will be seen that it is important to space the gelatin films on the belts 36 and 74 shown. The paper or cardboard when fed to the films extends beyond the edge thereof so that it will be in proper position to be stripped either by its own motion or by the stripping rollers shown. It is also desirable that the edges of the films be rec-

tilinear and extend transversely of the machine perpendicular to the edge of or the direction of travel of the belt. These edges of the films may in some operations act as gauges for the ends of the sheets being printed.

From the above description it will be seen that I have invented a very simple and efficient hectograph printing apparatus of the rotary press type. The apparatus can be used for performing several methods of hectograph printing as well as being used for stencil printing. As above set forth, the printed material may be simultaneously printed on both sides. In doing hectograph printing the ink on the master copy is much more efficiently used than in the methods and machines of the prior art. More uniform prints are also produced than in previous methods of hectograph printing. With the present apparatus cardboard can be very readily printed and easily stripped from the printing members. By having the travelling belt constructed and arranged to engage teeth on one or both of the cylinders over which it travels a very accurate movement of the belt is produced and any slipping is prevented. It is also an important feature of the invention that the apparatus may be constructed from machines now commonly used such as the "Multi-graph" or "Mimeograph" machines so that a much greater range of operation and usefulness for such machines is secured.

The method and apparatus have been amply demonstrated in actual practice and found to be very successful and efficient.

It will, of course, be understood that various changes may be made in the form, details, arrangement and proportions of the apparatus and in the steps and sequence of steps of the method without departing from the scope of applicant's invention, which generally stated, consists in a method and apparatus capable of carrying out the objects above set forth, such as disclosed and defined in the appended claims.

What is claimed is:

1. In a machine of the class described having in combination, two cylinders, a belt having spaced sections of hectograph gelatin composition thereon, said belt passing around and connecting the two cylinders and revoluble with said cylinders, images in hectograph ink in reverse on said sections of hectograph gelatin composition, means for pressing sheets of paper onto the said sections and against said images and means for stripping the said sheets of paper from said sections.

2. In a machine of the class described, the combination of a frame, two cylinders having peripheral surfaces, a belt having an outer surface of a hectograph gelatin composition and contacting on its inner surface the peripheral surfaces of the said cylinders and revoluble with the said cylinders, a supplementary cylinder secured to said frame adjacent to one of said cylinders, means for rotating the last two mentioned cylinders in contact with each other and at the same speed, said supplementary cylinder having a peripheral surface adapted to receive any one of a number of interchangeable printing members carrying images in hectograph ink, and means for securing one of said printing members to said peripheral surface.

3. In a machine of the class described, the combination of a frame, two cylinders having peripheral surfaces, a belt having sections of gelatin hectograph composition on its outer surface and contacting on its inner surface the

peripheral surfaces of the said cylinders and revoluble with the said cylinders, images in hectograph ink in reverse on one or more of said sections, a plurality of means for pressing a sheet of paper onto each of said sections and images, said means being located at different points on said frame and means for each of said means for stripping the same sheets of paper from the sections of gelatin hectograph composition.

4. In a machine of the class described, the combination of a frame, two cylinders having peripheral surfaces, a belt having sections of gelatin hectograph composition on its outer surface and contacting with its inner surface the peripheral surfaces of the said cylinders and revoluble with said cylinders, a supplementary cylinder secured to said frame adjacent to one of said cylinders, means for rotating the last two mentioned cylinders substantially in contact with each other and at the same speed, said supplementary cylinder being hollow and having a perforated peripheral wall, a stencil on the outer surface of the said perforated peripheral wall and means for inking said stencil.

5. In a machine of the class described, the combination of a frame, two cylinders having peripheral surfaces, a belt having sections of gelatin hectograph composition on its outer surface and contacting with its inner surface the peripheral surfaces of the said cylinders and revoluble with said cylinders, a supplemental cylinder secured to said frame adjacent to one of said cylinders, means for rotating the last two mentioned cylinders substantially in contact with each other and at the same speed, said supplementary cylinder being hollow and having a perforated peripheral wall, a stencil on the outer surface of the said perforated peripheral wall, means for inking said stencil, means for feeding a strip of paper between the outer surface of said belt and said stencil, said sheet of paper adhering to said belt and means for stripping said sheet of paper from said belt.

6. A printing apparatus having in combination, a rotary cylinder, means passing over said cylinder having thereon a gelatin hectograph film carrying an image in reverse, a member co-operating with said cylinder having a printing stencil thereon whereby a sheet of paper to be printed may be passed between said film and stencil and be simultaneously printed on both sides.

7. A machine of the class described having in combination, two spaced cylinders having substantially parallel axes, a belt running over said cylinders having an outer surface of hectograph gelatin composition, means for pressing a sheet of paper against said surface, one of said cylinders being of small diameter relative to the other whereby said belt makes a sharp turn around said smaller cylinder and stripping means adjacent said smaller cylinder with which said sheet of paper engages to be stripped from said belt.

8. In a machine of the class described having in combination, two cylinders, a belt having an outer portion carrying a body of hectograph gelatin composition connecting said two cylinders and rotating with said cylinders, means for pressing a sheet of paper against said body of gelatin with the front edge portion of said paper out of contact with said body and means for stripping said paper from said body of gelatin disposed in line with the front edge of said sheet whereby said sheet is engaged by said stripping means as said belt bends and passes around one of said cylinders.

9. In a machine of the class described having in combination, two cylinders spaced quite a distance, a belt having an outer portion carrying a body of hectograph gelatin composition extending about said cylinders and traveling with said cylinders in the rotation thereof, whereby said belt has a rectilinear portion between said cylinders, means for pressing a sheet of paper against said body of gelatin with its front edge portion out of contact with said body and means for stripping said paper from said gelatin engaged by said front edge portion of said paper as said belt and body of gelatin bend and move about one of said cylinders.

10. In a machine of the class described having in combination, two cylinders spaced quite a distance, a belt having an outer portion carrying a body of hectograph gelatin composition extending about said cylinders and traveling with said cylinders in the rotation thereof, whereby said belt has a rectilinear portion between said cylinders, means for pressing a sheet of stiff cardboard against said gelatin in said rectilinear portion whereby said cardboard will continue to move in a straight line and will be stripped from said gelatin as said belt and body of gelatin bends and moves about one of said cylinders.

FRED R. BARTHOLOMEW.
